CAR ROOF

Filed Jan. 10, 1921

Inventor:
Walter P. Murphy,
by ~~Samuel~~,
his attorneys.

UNITED STATES PATENT OFFICE.

WALTER P. MURPHY, OF NEW YORK, N. Y., ASSIGNOR TO P. H. MURPHY COMPANY,
OF PARNASSUS, PENNSYLVANIA, A CORPORATION OF PENNSYLVANIA.

CAR ROOF.

Application filed January 10, 1921. Serial No. 436,170.

To all whom it may concern:

Be it known that I, WALTER P. MURPHY, a citizen of the United States, and a resident of the city of New York, in the county 5 of New York and State of New York, have invented a new and useful Improvement in Car Roofs, of which the following is a specification.

This invention relates principally to 10 heavy gage steel car roofs comprising roof sheets which span the car from side to side and are riveted or otherwise secured together and to the car frame, and it relates more particularly to the manner of securing said 15 roof to cars having wood side plates.

The principal objects of the present invention are to obtain a waterproof eaves construction, to protect bolts which secure the roof to the substructure of the car, to 20 stiffen the eaves ends of the roof, to locate the securing rivets for the eaves ends of the sheet outside of the car, and to enable the roof to be assembled on a bench and applied to the car as a unitary structure. 25 Other objects are simplicity, strength, durability, and tightness. The invention consists principally in means hereinafter set forth for securing heavy gage steel roofs to cars having wood construction, and in the 30 combinations of parts hereinafter described and claimed.

In the accompanying drawing, which forms part of this specification, wherein like symbols refer to like parts wherever 35 they occur,

Fig. 1 is a vertical cross-section through the eaves portion of a car roof embodying my invention; and

Fig. 2 is a similar section showing a modified form of eaves construction.

The present roof comprises rigid load sustaining roof sheets 5 of heavy gage steel, arranged crosswise of the car and preferably extending from eaves to eaves in arcs 45 of circles. In Fig. 1, the side margins of adjacent sheets are lapped and rigidly secured together by means of rivets 6. In Fig. 2, the side margins of adjacent sheets are turned up at right angles forming side 50 flanges 7 which extend from end to end of the roof sheets. The side flanges are of the same height from the ridge to a point adjacent to the eaves where they merge into the plane of the body of the sheet. Pressed 55 sheet metal seam covers 8 of inverted U-

shape in cross-section embrace the side flanges 7 of adjacent sheets, and the seam covers and flanges are fastened together by rivets 9. The seam covers are provided with lateral base flanges 10 and decrease gradually 60 in height from the ridge towards the eaves, at which point they merge into the plane of their base flanges. The eaves end of the seam covers are turned down, as at 13, over the depending flanges 12 of the roof sheets. 65

In the construction shown in Figs. 1 and 2 the eaves ends of the roof sheets overhang the side plate 11 of the car and are turned down, as at 12. The overhanging eaves ends of the roof sheets have one flange of an eaves 70 angle strip 14 rigidly secured thereto by means of rivets 15. The eaves angle strips 14 extend lengthwise of the car and are disposed with their horizontal flanges uppermost and flush with the upper surface of 75 the side plate and extending outwardly therefrom and with the other or vertical flanges secured to the outer side of the side plate, and in the construction shown in Fig. 2 the vertical flange of the angle strip is 80 disposed in a longitudinal rabbet or recess 17 formed in the upper outer edge of the side plate 11^a and secured therein by means of a carriage bolt 16^a.

In the construction shown in 1 the upper edge of side sheathing boards 18 terminate below the lower edge of the eaves angle strip 14. In the construction shown in Fig. 1, the vertical flange of the eaves angle strip is secured to the outer face of the side 90 plate 11 by means of bolts 16. A wooden fascia 19 is secured to the side plate between the outer surface of said sheathing and the inner surface of the depending eaves flange of the roof sheet by means of nails 20. The 95 fascia 19 extends above the lower edge of the eaves flange of the sheet and below the top of the side sheathing, thereby covering the head of the securing bolt 16 and preventing rain or snow from entering the 100 space back of said fascia and thence reaching the interior of the car.

In the construction shown in Fig. 2, the side sheathing 18^a extends above the lower edge of the eaves angle to within a short 105 distance below the outwardly extending flange of said angle. A fascia 19^a is disposed between the sheathing 18^a and the depending flange 12 of the roof sheets. The top surface of the fascia bears against the 110

under side of the eaves angle and said fascia is secured to the side plate by nails 20* which are driven through the fascia and sheathing into the side plate. This construction also protects the bolt head and prevents water and snow from reaching the interior of the car.

In the constructions illustrated in the drawings, the fascia serves as a batten for the upper end of the sheathing and also protects the bolt heads and acts as means for weatherproofing the joint between the side plate and the side sheathing. If desired, a drive fit may be obtained between the fascia and the depending eaves flanges of the sheets owing to the flexibility of said eaves flanges.

One important advantage of the hereinbefore described constructions is that the roof sheets can be assembled and riveted to the connecting angle off the car before the same are applied to the car; that is, the whole roof may be assembled on the workshop floor or other convenient location and applied to the car as a unitary construction. When it is desired to remove a damaged sheet, the fascia can be removed and the rivets securing said sheets to the eaves angle can be sheared, as the removal of the fascia allows ample room for cutting and redriving these rivets. If desired, the nuts can be placed on the outside of the side plate, thereby permitting the removal of the eaves angle from the outside of the car, although, in actual practice, it is preferable to have the nuts on the inside for the sake of inspection and to enable the nuts to be tightened without removing the fascia.

What I claim is:

1. An eaves construction for car roofs comprising a side plate, metallic roofing extending outwardly beyond the outer face of said side plate, an angle having one flange secured to the outer face of said side plate and having its other flange projecting therefrom and secured to the under side of said roofing, the eaves end of said roofing being turned down beyond the outer edge of the outwardly projecting flange of said angle, side sheathing secured to the outer face of said side plate, and a fascia disposed be-

tween said side sheathing and the downward eaves end of said roofing and extending above the lower edge of said downturned end with its inner face flush with the outer 55 face of said siding.

2. An eaves construction for car roofs comprising a side plate, metallic roofing extending outwardly beyond the outer face of said side plate, an angle having one flange 60 secured to the outer face of said side plate and having its other flange projecting outwardly therefrom and secured to the under side of said roofing, the eaves end of said roofing being turned down beyond the outer 65 edge of the outwardly projecting flange of said angle, side sheathing secured to the outer face of said side plate with the upper edge thereof terminating below said angle, and a fascia disposed between the downturned eaves end of said roofing and the side sheathing, said fascia extending above 70 the lower edge of the downturned portion of said roofing and below the upper edge of said siding, with its inner surface flush with 75 the outer surface of said side sheathing and with its outer surface in contact with the turned down eaves portions of said roof sheets.

3. An eaves construction for car roofs 80 comprising a side plate, side sheathing secured to the outer face of said side plate with the upper edge thereof disposed below the upper surface of the side plate, a fascia of substantially rectangular section secured 85 to said sheathing and extending above the upper edge thereof and forming in connection therewith and with said side plate a vertical groove whose width corresponds to the thickness of said sheathing, metallic 90 roofing extending outwardly beyond the said side plate and having its eaves end turned down over the outer edge of said fascia, and an angle bar disposed with one flange in said groove and secured to said 95 side plate and with the other flange up and extending outwardly and secured to the under side of said roofing.

Signed at New York, New York, this 8th day of January, 1921.

WALTER P. MURPHY.

Certificate of Correction.

It is hereby certified that in Letters Patent No. 1,472,187, granted October 30, 1923, upon the application of Walter P. Murphy, of New York, N. Y., for an improvement in "Car Roofs," errors appear in the printed specification requiring correction as follows: Page 1, line 79, after the word "plate" strike out the comma and insert a period and the words *In the construction shown in Fig. 1, the vertical flange of the eaves angle strip is secured to the outer face of the side plate 11 by means of bolts 16*; same page, line 85, before the numeral "1" insert the word *Fig.*; same page, line 88, commencing with the word "In" strike out all to and including the numeral "16," line 91; and that the said Letters Patent should be read with these corrections therein that the same may conform to the record of the case in the Patent Office.

Signed and sealed this 8th day of January, A. D., 1924.

[SEAL.]

KARL FENNING,
Acting Commissioner of Patents.
